UNITED STATES PATENT OFFICE.

BENJAMIN B. DOWELL, OF WASHINGTON, DISTRICT OF COLUMBIA.

DESIGN FOR A VANITY CASE.

Application filed March 28, 1923. Serial No. 5,625. Term of patent 14 years.

To all whom it may concern:

Be it known that I, BENJAMIN B. DOWELL, a citizen of the United States, residing at Washington, in the District of Columbia, have invented and produced a new and original Design for Vanity Cases, of which the following is a specification, reference being had to the accompanying drawings, forming a part thereof.

In the aforesaid drawings,

Fig. 1 is a perspective view of the vanity case;

Fig. 2 is a similar view looking at the opposite side thereof;

Fig. 3 is a perspective view similar to

Fig. 1, the suspension strap being removed and the exterior mirror-carrying cover being shown in raised position; and

Fig. 4 is a perspective view similar to Fig. 2, looking at the opposite side thereof.

I claim:

The ornamental design for a vanity case substantially as shown.

In testimony whereof I have signed my name in the presence of two subscribing witnesses.

BENJAMIN B. DOWELL.

Witnesses:

LOUISA J. MILLS,
ROBERT T. HOGAN.
